UNITED STATES PATENT OFFICE.

ALEXANDER M. WATERWORTH, OF BALTIMORE, MARYLAND, ASSIGNOR OF ONE-HALF TO THOMAS T. A. HITAFFER, OF SAME PLACE.

BATH-TUB.

SPECIFICATION forming part of Letters Patent No. 310,344, dated January 6, 1885.

Application filed January 23, 1884. (No model.)

To all whom it may concern:

Be it known that I, ALEXANDER M. WATERWORTH, residing at Baltimore city, Maryland, have invented certain new and useful Improvements in Bath-Tubs, of which the following is a specification, reference being had to the accompanying drawings, forming part hereof, in which—

Figure 1 is a sectional view through part of the bottom of a bath-tub, showing my invention applied thereto, and Fig. 2 is a plan view of the same. Fig. 3 is a detached section on line *x x*, Fig. 1.

Like letters of reference mark like parts in all the figures.

My invention has for its object to permit ready access to the interior of the waste-well in bath-tubs; and to this end it consists in the construction, arrangement, and combination of parts, which will be first fully described hereinafter, and then specifically pointed out in the claim.

Referring to the drawings by letter, A is the bottom of the bath-tub; B, the waste-well; C, the plate covering the waste-well, and D the stopper for closing the opening through the plate C, said opening being formed by drawing out or flanging the metal of said plate, or casting a flange, *c*, as part thereof. The bottom 30 of said flanged opening is provided with grating *c'*. The stopper D is provided with a suitable ring, *d*, for lifting it. The waste-well B consists of sides *b*, bottom *b'*, and flanges *b''*, and is provided with a nipple, *b'''*, for the proper attachment of a waste-pipe, *b'''*. The bottom

5 A of the bath-tub rests on the flanges *b''* of the waste-well, and has soldered or otherwise secured to it in a perforation or opening which comes over the waste-well a double-flanged ring, *a' a'' a'''*. The plate C is secured to the 40 flange *a'''* of said ring by screws *a''* or other equivalent removable fastenings, a ring of packing, *a'''*, being inserted between the flange *a'''* and plate C to make a tight joint.

Should it be desired at any time to have access to the waste-well for cleansing or other purposes, it is only necessary to remove the screws *a''*, take out the ring *a'''* and plate C, and the interior is fully exposed to view, to remove any obstruction to the free flow of 50 water.

The device is adapted for attachment in tubs of zinc, iron, or stone, the bottoms in iron and stone tubs being rabbeted out to receive the flange *a'*, if desired.

Having thus described my invention, what I claim, and desire to secure by Letters Patent, is—

55 A bath-tub, in combination with a well, B, having a cover, C, a stopper, D, the flanged rim *a' a'' a'''*, and packing *a'''*, as and for the purpose set forth.

In testimony whereof I have hereunto set my name in presence of two subscribing witnesses.

ALEXANDER M. WATERWORTH.
